UNITED STATES PATENT OFFICE.

JOHN EASTBURGH, OF MOUNT JEWETT, PENNSYLVANIA.

ROTARY ENGINE.

SPECIFICATION forming part of Letters Patent No. 651,838, dated June 19, 1900.

Application filed February 20, 1900. Serial No. 5,890. (No model.)

To all whom it may concern:

Be it known that I, JOHN EASTBURGH, a citizen of the United States of America, residing at Mount Jewett, in the county of McKean 5 and State of Pennsylvania, have invented certain new and useful Improvements in Rotary Engines, of which the following is a specification, reference being had therein to the accompanying drawings.

10 This invention relates to steam-engines, and particularly to that class known as "rotary engines, concentric piston."

The object of the invention is to produce a 15 rotary engine comprising a novel form of piston, novel valve-shipping mechanism, and novel means for supplying steam to the piston and for conducting the exhaust.

Finally, the object of the invention is to 20 produce a rotary engine possessing advantages in points of simplicity, durability, and efficiency, proving at the same time comparatively inexpensive.

With the above and other objects in view 25 the invention consists in the details of construction and in the arrangement and combination of parts to be hereinafter more fully set forth and specifically claimed.

In describing the invention in detail reference will be had to the accompanying drawings, forming part of this specification, wherein like characters denote corresponding parts in the several views, in which—

Figure 1 is a plan view of a rotary engine embodying the invention. Fig. 2 is a view 35 in elevation of the end, showing the valve-shipping mechanism. Fig. 3 is a sectional view on the line 3 3 of Fig. 1, showing the piston in elevation. Fig. 4 is a sectional view on the line 4 4 of Fig. 2 with the shaft 40 and pipe in elevation; and Figs. 5 and 6 are plan views of the inner ends of the packing-boxes.

In the drawings, A and A' denote the cylinder-heads, each having annular recesses, 45 semicircular in cross-section, which form the cylinder *a* when the parts are assembled. The cylinder-heads are bolted to a rectangular frame *b*, and the shaft of the cylinder is journaled in bearings *d*, attached to said 50 frame. A steam-supply pipe *e* and a steam-exhaust pipe *f* are connected to the cylinder-

heads and communicate with the interior of the cylinder through the holes *e'* and *f'*. The cylinder-heads are formed with central apertures to receive the combined packing-boxes 55 and steam-chests, and in forming the combined packing-boxes and steam-chests a cylindrical casing *g'* is employed and near the end provided with head *g*², having a central aperture for the shaft. I also provide a series of ports 60 *g*³ for the passage of the steam or exhaust. Between the central aperture and the ports there is an annular partition *x* to encircle the shaft and confine the packing. Between the partition and the outer wall is an annular 65 spaceway. The steam from the pipe *e* passes into the space and from there through the ports to the cylinder. An annular flange *i* projects beyond the head *g*² of the combined packing-box and steam-chest, designed to fit 70 close to the surface of the piston *j*, said piston being keyed to the shaft. The plates *h* serve to regulate the pressure of the packing in the well-known manner. The piston is provided with a radial inlet-port 1, terminating 75 in a curved portion opening on the side of the piston next to the steam-supply pipe. The piston has also a radial exhaust-port 2, oppositely disposed with relation to the inlet-port. The piston-head 80 *g* is of such shape as to fit within the chamber of the cylinder, and it is circular in cross-section. Each end of the piston-head is recessed, as shown at 4; and ports 5 register with the inlet-port and exhaust-port, the ports 85 5 terminating in the recesses of the piston-head. Valve-blades 6 operate through slots in the cylinder-head, each alternately controlling the chamber and forming an abutment for the live steam as it emerges from 90 the piston-head. The manner of operation will be apparent to those familiar with the art.

The valve-shipping mechanism comprises a cam 7, mounted on the engine-shaft, a lever 8, acting after the manner of a walking-beam 95 pivoted in bearings formed by the posts 9, and valve-rods 10, connected to the lever 8 by links 11. Posts 12 are provided at each side of the valve-rods, and plates 13, supported by the posts, have apertures in which the valve-rods are guided. Antifriction-rollers 14 are mounted on the lever in position

to engage the cam, and the rollers are held in place between two shoulders or enlargements 15 on the lever.

In securing the piston-head to the piston I employ (bolt on each end of piston-head) straps M, looped around and embedded in the piston-head, with the ends projecting to the piston-collar to make a close fit between the parts. I also employ packing-straps N, which exert pressure outwardly and cause the outer surface of the straps to fit closely against the cylinder-heads. The piston is also connected to the piston-head by pins O for the purpose of effecting a rigid connection between the parts.

Having thus fully described my invention, what I claim as new, and desire to secure by Letters Patent, is—

1. In a rotary engine, two cylinder-heads having annular recesses forming a cylinder when the parts are assembled, a steam supply and exhaust pipe connected to the said cylinder-heads and communicating with the interior of the cylinder, the said cylinder-heads having central apertures, combined packing-boxes and steam-chests adapted to fit in said apertures, the combined packing-boxes and steam-chests consisting of a cylindrical casing having a central aperture and a series of ports, a partition between the central aperture and ports forming a space between the partition and outer wall, a flange projecting beyond the head of the combined packing-box and steam-chest, a plate to regulate the pressure of the packing, a power-shaft fitting in the central aperture of the cylinder-heads, a piston on the shaft, a piston-head having recesses in its ends and ports connecting the recesses with the ports of the cylinder-heads, valves, and valve-shipping mechanism, as and for the purpose described.

2. In a rotary engine, two cylinder-heads having annular recesses forming a cylinder when assembled, a steam supply and exhaust pipe connected to the cylinder-head and communicating with the interior of the cylinder, the said cylinder having central apertures, combined packing-boxes and steam-chests adapted to fit in said apertures consisting of a cylindrical casing provided near the end with a head having a central aperture and a series of ports, a partition between the central aperture and ports, a flange projecting beyond the head of the combined packing-box and steam-chest, a plate to regulate the

pressure of the packing, a power-shaft fitting in the central apertures of the cylinder-heads, a piston on the shaft, said piston having a radial inlet-port terminating in a curved portion opening on the side next to the supply-pipe and also having a radial exhaust-port oppositely disposed with relation to the inlet-port, a piston-head adapted to fit within the chamber of the cylinder, having a recess in its ends and having ports registering with the inlet and exhaust port of the cylinder-head and terminating in the recesses of the piston-head, said piston-head being secured to the piston by bolts, straps looped around and embedded in the piston-head with the ends projecting to the piston-collar, the straps adapted to exert an outward pressure, and pins forming a rigid connection between the piston and piston-head, valve-blades operating through slots in the cylinder-head and valve-shipping mechanism, as and for the purpose described.

3. In a rotary engine, two cylinder-heads having annular recesses forming a cylinder when assembled, a steam supply and exhaust pipe connected to said cylinder-heads and communicating with the interior of the cylinder, the said cylinder-heads having central apertures, combined packing and steam chests adapted to fit in said apertures consisting of a cylindrical casing having a central aperture and a series of ports, a partition between the central opening and ports forming a space between the partition and outer wall, an annular flange projecting beyond the head of the combined packing-box and steam-chest, a plate to regulate the pressure of the packing, a power-shaft fitting in the central apertures of the cylinder-heads, a piston on the shaft, a piston-head having recesses in its ends and ports connecting the recesses with ports of the cylinder-heads, valve-blades operating through slots in the cylinder-heads and shipping mechanism comprising a cam mounted on the engine-shaft, a lever suitably pivoted, valve-rods, links connecting the valve-rods and lever, guides for the valve-rods and anti-friction-rollers adapted to engage the cam, as and for the purpose described.

In testimony whereof I affix my signature in the presence of two witnesses.

JOHN EASTBURGH.
